UNITED STATES PATENT OFFICE

CHARLEY FRY, OF DENVER, COLORADO, ASSIGNOR OF ONE-HALF TO FOSTER CAPSTICK, OF DENVER, COLORADO.

WASHING-POUNDER.

1,150,817.

Specification of Letters Patent.

Patented Aug. 17, 1915.

Application filed July 20, 1912. Serial No. 710,557.

To all whom it may concern:

Be it known that I, CHARLEY FRY, citizen of the United States, residing in the city and county of Denver and State of Colorado, have invented certain new and useful Improvements in Washing-Pounders; and I do declare the following to be a full, clear, and exact description of the invention, such as will enable others skilled in the art to

10 which it appertains to make and use the same, reference being had to the accompanying drawings, and to the characters of reference marked thereon, which form a part of this specification.

15 My invention relates to improvements in washing pounders of the character in which a conical metallic shell is connected at its smaller extremity with a stem, or handle, a plate being located a short distance from the 20 other extremity of the shell, which is provided with openings through which the water enters the shell as the pounder is brought into contact with the clothes which are immersed in water for the purpose.

25 In this character of device, the upper portion of the shell, or that near the handle, is perforated to permit the escape of the air as the water rushes into the conical chamber of the shell through the openings in the 30 plate. Furthermore, there is a frusto-conical shield applied to the shell which surrounds the perforated portion of the latter, but is offset from the shell in the zone of the perforations to permit the escape of the 35 air and water, and whereby this discharge is in a downward direction.

My improved construction contains a number of novel features. In the first place, the plate is reinforced by radial ribs which 40 are struck out of the body of the plate by a suitable stamping die, the center of the plate being also pressed out of the plane of the plate the same distance as the depth of the inner extremities of the strengthening ribs.

45 This central part is perforated to receive a rod which passes through the center of the plate, its opposite extremity being threaded to enter the inner extremity of the handle, a nut being applied to the plate extremity of 50 the rod whereby the plate is secured in its proper position on the shell. Furthermore, the shield which surrounds the perforated portion of the shell is provided with inwardly pressed parts whose position may

be caused to coincide with that of a number 55 of perforations in the shell whereby the passage of fluid through these perforations may be regulated and controlled.

Having briefly outlined my improved construction, I will proceed to describe the same 60 in detail, reference being made to the accompanying drawing, in which is illustrated an embodiment thereof.

In this drawing: Figure 1 is a sectional view of the device cutting the shell and its 65 attachments, the inner extremity of the handle being also shown in section, on the line 1—1, Fig. 2. Fig. 2 is an end elevation of the larger extremity of the shell and the plate, or cover, applied thereto. Fig. 3 70 is a cross section taken on the line 3—3, Fig. 1.

The same reference characters indicate the same parts in all the views.

Let the numeral 5 designate the shell, or 75 body, member of the device, to which is applied, near its outer extremity, a plate, or cover 6, the outer edge of the said plate engaging a circumferential shoulder 7 formed on the shell, the larger portion of the shell 80 beyond the shoulder being offset for the purpose. This shell is provided with a number of perforations 7, in which are inserted short tubes, or sleeves 8, the inner extremities of the sleeves being crimped to the 85 plate, the edge of the latter engaging the sleeve between the circumferential bead 9 and the inner flange 10. The body of each sleeve, or short tubular member, extends beyond the plate in the direction of the larger 90 extremity of the shell. These sleeves are slightly frusto-conical in shape, whereby the water, as it passes therethrough, enters the chamber of the shell with greater force than would be the case if these parts were cylindrical.

The plate 6 is provided with a number of radial ribs 12 which extend outwardly from a part 13 which is pressed out of the plane of the body of the plate and forms a seat 100 for a milled nut 14 which is threaded upon one extremity of a rod 15, the opposite extremity of the rod being formed into a wood screw 16 which is threaded into the inner extremity of a handle 17. The inner 105 end of the handle extends into the smaller extremity of the shell as shown at 18 and forms a support therefor, the smaller ex-

tremity of the shell fitting the handle closely a short distance beyond the inner extremity of the latter.

Attention is called to the fact that the ribs 5 12 are struck out of the body of the plate, which is an important feature from a stand-point of economy, as compared with a construction where these ribs are applied to the plate by soldering, or otherwise.

10 The inner extremity of the handle is inserted in a ferrule 19 which is formed integral with a frusto-conical shield 20 applied to the smaller extremity of the shell adjacent the handle, the said shield extending 15 toward the larger extremity of the shell far enough to cover perforations 21 formed in the shell for the escape of air and water during the use of the device, whereby a relatively strong suction is produced. The part 20 of the shield which surrounds the shell 5 is offset in the zone of the perforations as shown at 22, and is provided with a number of inwardly pressed parts 23, with reference to which the shell may be so adjusted that 25 the parts 23 occupy positions coincident with that of a number of the perforations 21, thus retarding the passage of air and water when such result is desirable. As shown in the drawing, there are only half as many 30 stop parts 23 as there are perforations 21, since it is never desirable to completely interrupt the passage of air and water through the perforations 21.

In assembling the parts of my improved 35 construction, the shell 20 is applied to the handle by inserting the latter in the ferrule 19, the inner extremity of the handle extending beyond the ferrule, as shown at 18, to form a support for the smaller extremity 40 of the shell. The wood screw extremity 16 of the rod is screwed into the handle and the shell applied to the handle, whose part 18 is surrounded by the smaller extremity of the shell, as best illustrated in Fig. 1, the 45 handle extending inwardly beyond the smaller end of the shell to form a stable support therefor. The plate disk, or cover 6, is then put in place, whereby its outer edge rests upon the shoulder 7 of the shell and the 50 perforation 24 formed in the central part is caused to receive a threaded end 25 of the rod, this threaded end extending beyond the

raised seat 13 for the nut 14. This nut is then applied to the rod whereby the shell is tightly secured to the handle, being 55 clamped between the plate 6 and the handle by means of the rod and nut.

The strengthening ribs and nut seat 13 which are struck out of the plate, or cover 6, are important features, since they reinforce 60 the said plate, giving the same the necessary stiffness and rigidity for the purpose. It must be understood that this plate is subjected to considerable pressure when the device is in use, and by means of the struck 65 up parts 12 and 13 the necessary strength and rigidity are given the plate without making the latter of sheet metal, so heavy as would otherwise be required.

From the foregoing description it will be 70 understood that my improved construction is such that the entire device may be readily taken apart and thoroughly cleaned and dried after using the same, thus making it 75 a perfectly sanitary article and preventing any accumulation of dirt or foreign matter in the chamber of the shell, which otherwise might occur if the parts were not separable for cleaning purposes, as heretofore explained.

Having thus described my invention, what I claim is:

The combination with a conical shell of a handle to which the smaller extremity of the shell is applied, said handle having an 85 end portion of reduced diameter, a shoulder formed by the junction of this smaller portion with the handle proper, a ferrule surrounding the smaller portion of the handle above the shell and rotatable on the shell and abutting against the said shoulder, the ferrule merging into a frusto-conical shield surrounding the smaller extremity of the shell, the latter being perforated and the shield being offset adjacent the perforations 90 and provided with inwardly extending projections adapted to be thrown into or out of register with the perforations of the shell.

In testimony whereof I affix my signature in presence of two witnesses.

CHARLEY FRY.
